UNITED STATES PATENT OFFICE.

WILLIAM R. CONCIE AND CHARLES H. SMITH, OF HILLYARD, WASHINGTON.

DOOR-BUFFER.

1,119,346.

Specification of Letters Patent.

Patented Dec. 1, 1914.

Application filed November 17, 1913. Serial No. 801,534.

To all whom it may concern:

Be it known that we, WILLIAM R. CONCIE and CHARLES H. SMITH, citizens of the United States, residing at Hillyard, in the county of Spokane and State of Washington, have invented a new and useful Door-Buffer, of which the following is a specification.

This invention relates to improvements in door stops.

It is one of the objects of this invention to provide a door stop with a buffer for arresting opening movement of the door and a retainer for arresting rebound closing movements which succeed the arresting movement under the action of the buffer so as to provide means which will engage the door on opposite sides thereof.

In order to avoid shocks and jars incident to arresting movement of a door, I provide a buffer which offers cumulatively increasing resistance to opening movement of the door so as to neutralize all shocks and jars.

Other features of novelty will be more fully described in connection with the accompanying drawing and will be more particularly pointed out in and by the appended claims.

In the drawing:—Figure 1 is a perspective view of one form of door stop embodying a form of our invention. Fig. 2 is a view thereof in side elevation applied to a floor and illustrating a door in engagement therewith. Fig. 3 is a perspective view of a modified form of our invention. Fig. 4 is a view similar to Fig. 2 showing the application of the form shown in Fig. 3. Fig. 5 is a sectional view on line 5—5 of Fig. 1.

Like characters of reference designate similar parts throughout the different figures of the drawing.

Referring first to the forms shown in Figs. 1, 2 and 5, 1 designates the base section or portion which is adapted to rest or be secured on a floor surface and which forms an intermediate portion of a door stop composed of a strip of spring metal. One end portion 2 is bent in overhanging relation with the base portion 1 and is substantially parallel therewith for a limited distance as indicated at 3. The remainder of the portion 2 normally lies at an acute angle to the base portion 1 and its terminal end 4 is bent downwardly and backwardly under the inclined portion 2 but is disposed in spaced relation with respect thereto so as to afford

an initial resistance against opening movement of the door, as will presently appear. In the opening movement of the door, the lower edge thereof will traverse the upper face of the inclined portion 2 and depress the same as the door passes thereover. Depression of the portion 2 offers a slight initial resistance to the door but the primary initial resistance is afforded when the door passes over the end portion 5 and collapses the same upon the bent portion 4, which latter will have been forced down into engagement with base 1 so that it will be necessary for the door to compress the bent terminal end, against the resistance thereof, in order to pass over it. Immediately after the door has passed over it the bent portion 2, which is the retainer, this retainer will spring up, as shown in Fig. 2, so as to arrest rebounding or return movement of the door which results from its engagement with the buffer, which we will now describe.

The remaining end of the strip is bent upwardly, as indicated at 6, and is inclined 80 toward the door with respect to the direction of opening movement thereof. The terminal end 7, is bent downwardly so as to lie in a substantially vertical position and form an impact face against which the door 85 will strike in flat abutting relation. This portion constitutes the buffer of our improved stop and it will be seen that the yielding resistance which it first offers will be supplemented by the subsequent resist- 90 ance offered by part 6 so that the buffer will offer a cumulatively increasing buffer resistance which will not only arrest opening movement of the door but which will completely neutralize all shocks and jars in the 95 performance of such function.

When the device of our invention is positively anchored to the floor we may provide a screw hole 8 at one portion of the base. A screw hole 9 is disposed near the other end 100 of the base 1 and in order to facilitate insertion of a screw thereto we provide a relatively enlarged opening 10 in the parallel portion 3 which is in registry with the opening 9.

Next referring to the modified form shown in Figs. 3 and 4, 11 designates a buffer which is formed in a manner to offer a cumulatively resisting buffer action to opening movement of the door and which is 110 constructed in spiral form. Impact of the door thereagainst will act to increasingly

distort the spiral so that the latter will gradually arrest the door and neutralize all shocks and jars in so doing.

It will be seen that in both forms of our invention we provide a folded overturned spring end to form a buffer.

The action of the retainer 12, in the form shown in Figs. 3 and 4 is the same as in the preferred construction. Screw openings 13 10 may be provided near one end of the base 14, and near the other end thereof we provide marginally disposed openings 15. In order to facilitate insertion of the screws in openings 15 we preferably reduce or cut 15 away the retainer 12, as indicated at 16.

It is believed that the novelty and utility of our invention will be fully understood from the foregoing description, and while we have herein shown and described specific 20 forms of our invention we do not wish to be limited thereto except for such limitations as the claims may import.

We claim:

1. A door stop comprising a strip of 25 spring metal having a base portion adapted to rest upon the floor and provided with a buffer formed by bending one end upwardly at an inclination to the vertical and toward the door with respect to the opening movement thereof, the terminal of said upwardly 30

bent portion being bent downwardly and lying substantially vertically and in normal spaced relation with respect to said upwardly bent portion, whereby an accumulatively increasing buffer resistance is successively offered to opening movement of the door first by the free end and then by the bent up portion against which the free end finally abuts, substantially as described. 35

2. A door stop comprising a strip of 40 spring metal having a base portion adapted to rest upon the floor and provided with a bent up end buffer portion, the remaining end being bent to lie above and at an acute angle to the base portion for depression by 45 the door when the same passes thereover, the terminal end portion of said remaining end being bent upon itself for spring compression by the door against the base portion whereby an initial resistance is offered 50 to the latter, substantially as described.

In witness whereof we hereby affix our signatures in the presence of two subscribing witnesses.

WILLIAM R. CONCIE.
CHARLES H. SMITH.
